UNITED STATES PATENT OFFICE.

WILLIAM J. MORGAN, OF BARTON, OHIO.

PERMUTATION-PADLOCK.

1,268,755.

Specification of Letters Patent.

Patented June 4, 1918.

Application filed November 12, 1915. Serial No. 61,099.

To all whom it may concern:

Be it known that I, WILLIAM J. MORGAN, a citizen of the United States, residing at Barton, in the county of Belmont and State 5 of Ohio, have invented new and useful Improvements in Permutation - Padlocks, of which the following is a specification.

The present invention relates to improvements in permutation padlocks.

10 An object of the invention is to construct a padlock having few parts, wherein the casing is provided with a dial face and a plurality of arbor carrying hands adapted to be revolved upon the casing to be brought 15 into register with certain of the characters on the dials, the arbors being provided with tumblers having gates or notches, the same being normally engaged by a lug provided upon a slide which also engages in the notch 20 in the shackle and which, when the said notches or gates are brought into alinement with the said lug, will permit of the actuation of the slide to bring the same out of contacting engagement with the shackle to 25 permit of the opening of the lock.

With the above and other objects in view, the improvement resides in the construction, combination and arrangement of parts set forth in the following specification and falling 30 within the scope of the appended claims.

In the drawings:

Figure 1 is a view of a permutation padlock constructed in accordance with the present invention,

35 Fig. 2 is a view looking toward the rear of the same,

Fig. 3 is a view approximately on the line 3—3 of Fig. 1,

Fig. 4 is a sectional view approximately 40 on the line 4—4 of Fig. 2,

Fig. 5 is a sectional view approximately on the line 5—5 of Fig. 4, with the tumblers having their gates or notches in position to receive the lug provided upon the slide, and 45 the said slide moved into engagement with the said notches to permit of the automatic opening of the shackle,

Fig. 6 is a sectional view approximately on the line 6—6 of Fig. 1,

50 Fig. 7 is a perspective view of the shackle,

Fig. 8 is a perspective view of the lug carrying slide,

Fig. 9 is a perspective view of one of the hands and the arbor arranged thereon,

55 Fig. 10 is a similar view of the other hand

and its arbor and showing the disk or tumbler members associated therewith,

Fig. 11 is a face view of the lock, the hands being removed therefrom, and

Figs. 12 to 15 illustrate the tumblers. 60

In carrying out my invention I provide a flanged circular casing 1 which has arranged therein the tumblers of the lock. It may be here stated that it is primarily my purpose to have the tumblers arranged at 65 the factory during the manufacture of the locks, so that each of the locks sent out from the factory will have a different combination and of course the purchaser will be informed of the proper combination. 70

As illustrated in the drawings the device is a padlock, and the outer face, indicated by the numeral 2, is provided with a central aperture 3, while the inner or back face 4 is formed with an elongated slot 5 through 75 which passes the stem 6 of a slidable member 7. The slidable member 7 includes a flat plate 8, and the stem 6 is secured to the plate adjacent one of the ends of said plate, the outer end of the stem 6 being provided with 80 a milled head 6' which contacts with the outer face of the rear plate of the lock casing, it being understood that the plate 8 is arranged upon the interior of the casing and also contacts with the inner face of the said 85 back plate of the said casing. The plate 8 is influenced by a spring 9 that is secured in the casing in any desired manner, whereby the said plate is normally moved in one direction. The plate 8 upon the inner face 90 thereof is provided with an inwardly extending lug 17 and one of the edges of the said lug may be provided with a reduced portion providing a tongue 18.

The shackle for the lock is indicated by 95 the numeral 13 and the longer leg 14 thereof passes through a suitable opening 11 in the top of the lock casing, the said leg 14 also passing through an opening in a suitable supporting plate 22 that is secured in the 100 lock casing. The end of the leg 14 is provided with a depression within which is seated a spring 20 that exerts a tension between the inner wall of the depression and the lower wall of the casing or a lug provided upon the said lower wall of the casing to move the shackle longitudinally in an 105 outward direction with relation to the casing. This outward movement is limited by stop members 21 provided upon the leg 14 110

which are adapted to contact with the referred to plate 22. The longer leg 14 is provided with a transverse notch 15 and the spring 9 is designed to move the plate whereby to cause the lug 17 thereof to be received in the said notch 15 to retain the shackle in locked position. The shorter leg 19 of the shackle 13 also passes through a suitable opening 19' in the top of the casing when 5 the shackle is in locked position, and the numeral 23 designates an angularly disposed plate arranged in the casing below the said opening 19'. This plate not only provides a stop for limiting the inward movement of 10 the shackle to bring the notch 15 of the leg 14 thereof into alignment with the lug 17 of the plate 8, but also prevents the insertion of an instrument through the opening 19' to interfere with the alignment of the 15 tumblers in the lock, which will hereinafter be referred to in detail. The outer face of the casing has impressed thereon a number of indicating characters, indicated by the numeral 24, the numerical characters as 20 shown in the drawings ranging from 1 to 30, so that the plate 2 provides a dial face.

The dial face, adjacent the opening 3 therein is provided with a plurality of depressions 25, one of which being arranged 30 radially of each of the indicating characters 24, and these depressions 25 are adapted one to receive a spring actuated detent 25' provided upon the inner face or body portion of an indicator 26 the same being provided 35 with a hand 27. The hand, adjacent its indicating or pointer portion is provided with an outwardly extending lug or finger piece 28, and the said body is centrally provided with an arbor 29 which passes through the 40 opening 3 in the plate 2 of the lock. The arbor 29 comprises a hollow tubular member and has secured thereon a disk 31, the said disk having a peripheral notch 32. Arranged upon the arbor 29 between the 45 notched disk 31 and the outer face 2 is a pressure spring 33 which is adapted to bring the spring actuated detent 25' to within one of the depressions 25 upon the plate 2 thus retaining the pointer member of the hand in 50 alignment with one of the indicating characters 24 upon the face 2.

Loosely arranged upon the arbor 29 and resting upon the disk 31 is a similar disk 34. This disk 34 has a peripheral notch 35 and 55 is further provided preferably approximately opposite the notch 35 with a lateral extension or finger 36, the said finger being disposed a suitable distance away from the arbor 29. Also loosely arranged upon the 60 arbor 29 is a plurality of disk members or tumblers 37, 38 and 39. These tumblers are in the nature of disks and are provided with peripheral notches or gates 40, and the tumblers are retained against normal rotary 65 movement through the medium of support

ing spring plates in the nature of frames 41 which are arranged between the center and the two outer disks and which contact with the opposite faces of the inner disk or central disk and the inner faces of the outer 70 disks. Each of the disks is formed with a concentric slot 42, the said slots varying in length, and through each of said slots is passed the finger 39 of the disk 34.

Passing through the hollow arbor 29 of 75 the indicator member 26 is the rounded portion of the stem or arbor 43 for an indicating finger 44, the last mentioned finger being disposed over and rotatable upon the body of the indicator 26. The indicating point or 80 member of the last mentioned finger is adapted to contact with the offset finger member 28 of the member 27, to limit the rotary movement of the last mentioned finger upon the member 26, and this finger 85 is adapted to be brought into register with certain of the indicating marks 24 upon the face 2 of the casing to reach the proper combination as will presently be described. The inner end of the arbor 43 is square to receive the square bore of a disk 47, the said disk having a peripheral notch 48 corresponding with the notch 35 in the disk 34 and having an opening 50 to receive the finger 36 of the said disk 34. Thus it will be 90 noted that the disks 34 and 47 are connected and are adapted to be rotated in unison when the indicating member 44 is rotated upon the indicating member 26.

The operation of the device may be briefly 100 described as follows: It is, of course, understood that the operator is acquainted with the proper operation whereby all of the notches in the disks and tumblers will be brought to align with the tongue 18 on the lug 17 of the slidible member 7, whereby the said member may be moved to bring its lug out of engagement with the notch 15 in the longer leg 14 of the shackle 13 to permit of the spring 20 moving the shackle outwardly of the lock. The member 26 is first turned to bring its finger 27 to register with one of the characters 24 upon the dial face so that the operator is assured that the notch 32 of the disk 31 is brought opposite the 115 tongue 18 of the lug 17. The disks 34 and 47 have their notches 35 and 48 alining and the said disks, through the medium of the stem or finger 36, are connected to the stem 43 of the indicating member 44. The member 44 is turned in opposite directions upon the member 26 to cause the finger 36 to engage with the opposite or end walls of the concentric slots 42 in the respective disks 37, 38 and 39. As these slots vary in lengths 120 it will be apparent that the operator must be well acquainted with the combination in order to manipulate the member 44 so as to bring the notches of the said disks 37, 38 and 39 into alinement with each other and into 125 130

alinement with the notch 32 of the disk 31. While the disks 37, 38 and 39 are loosely arranged upon the arbor of the member 36 the frictional engagement between the said 5 disks and the spring frame members 41-41 is such that the disks will not freely turn unless the end walls of their slots are contacted by the finger 36 so that when one of the disks has its notch properly alining with 10 the tongue 18 of the slidable member and the notch 32 of the disk 31, the said disk will be retained in such position until again contacted by the finger 36. When all of 15 the disks are brought to proper alinement with the notch 32 of the disk 31 and the tongue 18 of the slide 7 it will be apparent that a lateral pressure imparted upon the knob 6' of the slide will cause the plate 8 to be moved laterally in the casing bringing 20 the lug 17 out of the notch 15 of the shackle and the tongue 18 into engagement with the alining notches in the respective disks or tumblers.

Having thus described the invention, what 25 I claim is:

1. A permutation padlock including a casing having depressions in one of the faces thereof, a spring pressed shackle in the casing, a sliding member coacting with the shackle for securing the same in locked position in the casing, arbors in the casing one comprising a sleeve member receiving the other arbor, hands upon the exterior of the 30 casing for both the arbors, a notched disk secured to one of the arbors, a finger upon 35 said disk, notched tumbler members having arcuate slots of varying lengths disposed upon the said arbor and having the finger of the said disk received in the said slots, 40 a second notched disk secured to the inner

arbor and connected with the finger of the first mentioned notched disk and a spring detent upon one of the hands engaging with referred to depressions in the face of the 45 casing.

2. A permutation padlock including a casing, a shackle having a notched leg received in the casing, spring means for normally moving the shackle to an unlocking position, 50 a slideable member in the casing, a lug carried thereby and designed to engage in the notch of the shackle to hold the shackle in locked position, arbors, one comprising a sleeve and the other comprising a stem revolvably received in the sleeve arranged in the casing, operating members for the arbors arranged exteriorly of the casing, a notched disk secured to the sleeve, a plurality of other notched disks loosely arranged on the sleeve, 55 one of which being disposed adjacent the referred to fixed disks, and the remaining disks having arcuate slots of different lengths, means between the disks for normally retaining the same against movement 60 on the sleeve, a notched disk rigidly secured to the end of the stem projecting through the sleeve, and a finger member connecting the last mentioned disk with the referred to loosely arranged disk upon the sleeve adjacent the fixed disk, and said finger passing through the arcuate slots in the remaining disks, all as and for the purpose set forth. 70

In testimony whereof I affix my signature in presence of two witnesses.

WILLIAM J. MORGAN.
